(57) **CLAIM**

The ornamental design for a floor lamp, as shown and described.

DESCRIPTION

FIG. 1 is a front elevation view of a floor lamp showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of the encircled portion in FIG. 5; and,

FIG. 10 is an enlarged view of the encircled portion in FIG. 7.

The broken lines in the drawings illustrate portions of the article that form no part of the claimed design. The dot-dash broken lines depict boundaries of the enlarged view and form no part of the claimed design.
